OR D11,269 EX

DESIGN FOR VASES.

Design No. **11,269**, dated July 1, 1879

UNITED STATES PATENT OFFICE.

MELVILLE D. JONES, OF BOSTON, MASSACHUSETTS.

DESIGN FOR VASES.

Specification forming part of Design No. **11,269**, dated July 1, 1879; application filed May 19, 1879.
[Term of patent 7 years.]

To all whom it may concern:

Be it known that I, MELVILLE D. JONES, of Boston, county of Suffolk, and State of Massachusetts, have originated and designed a Vase, of which the following is a full, clear, and exact description, reference being had to the accompanying illustration, making part of this specification.

In this vase the bowl is comparatively shallow and cyathiform in shape, with pear-shaped panels B at bottom, having foliate backgrounds. The top of the bowl terminates in

an overhanging rim, C, while the pedestal D, which is comparatively high, is of the Corinthian order, concave in outline, and with a foliate pintle, while, finally, the base E is rectangular, with slightly-flaring sides.

What I claim as my invention is—

The design above described and as shown in the accompanying fac-simile.

MELVILLE D. JONES.
